SEALING MACHINE

William Stelzer, Detroit, Mich., assignor to Stoffel
Seals Company, Incorporated, New York, N. Y.,
a corporation of New York

Application April 17, 1942, Serial No. 439,435

6 Claims. (Cl. 81—9.1)

The invention relates to sealing machines or seal presses, and more particularly to a sealing machine to affix seals of the type described in my co-pending application, Serial #437,529, filed April 3, 1942, to a string or object in a speedy manner.

The object of this invention is to provide a power driven automatic seal press where the seals in the pre-fabricated shape are fed automatically and in proper order from a hopper to the press dies, and where the seals are secured to a cord or the like by the press dies which are responsive to the control exercised by an operator.

The invention aims at producing an improved mechanism for enclosing and securing the ends of a cord or wire within the hollow rim of a seal, particularly where one end of said cord is passed through one-half of the rim of the seal, and the other half is passed through the opposite half of the seal, said mechanism including means for producing an outward curl on the seal, as well as means to facilitate separation of the two ends of the cord by the operator.

Another object is to produce an improved hopper mechanism, particularly adapted for directing the seal cups or capsules to the dies in the proper position.

Further aims and advantages will appear by inspection of the accompanying drawings, wherein:

Fig. 1 is a sectional side elevation of the automatic sealing machine;

Fig. 2, a side elevation, partly in section, of the type of cup or capsule in the pre-fabricated shape used in conjunction with the novel sealing machine to produce a seal or tag;

Fig. 3, a sectional front elevation of the hopper mechanism and track leading to the die members, as seen in the direction indicated by arrow 1 of Fig. 1;

Fig. 4, a sectional side elevation of the hopper taken on line 4—4 of Fig. 3;

Fig. 5, a section taken on line 5—5 of Fig. 4;

Fig. 6, a section taken through the track on line 6—6 of Fig. 4; and

Fig. 7, a section taken on line 7—7 of Fig. 1.

Describing the invention now in detail and referring in particular to Fig. 1, there is shown a frame or base 5 to which the various parts of the automatic sealing machine are mounted. A drive shaft 6 revolving in the direction of arrow 7 represents the power means to operate the dies and the hopper. This shaft may be driven by any suitable source of power, a speed reduction unit driven by an electric motor being most

suitable. This unit is not shown on the drawings because it may be of conventional design and forms no part of this invention.

Mounted to shaft 6 and revolving therewith is a clutch member 8 having a bearing on which a cam 9 is revolvable. While shaft 6 and clutch member 8 are revolving in a counterclockwise rotation, cam 9 remains stationary when the machine is in the "off" position as shown on the drawings. This cam has pivotally mounted to it a pawl 10 movable about pin 11 and held out of engagement by a trip lever 12 against a stop 13 extending from cam 9, whereby a spring 14 is compressed which urges pawl 10 into engagement with clutch 8 when lever 12 is tripped by the operating lever 15 through connecting link 16.

When pawl 10 is engaged with clutch 8 cam 9 revolves in unison with drive shaft 6 to actuate lever 17 rotatable about stud 18 and having an anti-friction roller 19 rolling on the periphery of the cam. Lever 17 at its opposite arm has pivotally secured thereto a clevis 20 urged into a vertical position by a spring 21. A curling die 22 is adjustably secured to said clevis pin 20 and has within its lower extremity a slidable pin 23 urged into its ejected position by a spring 24, checked by a stop screw 25.

Also in contact with cam 9 is another roller 26 revolvable on a transfer or control lever 27 pivoted on stud 18 which is secured to frame 5. This lever serves to shift curling die 22 from one position into another through the intermediary of arm 28 urged in a counterclockwise rotation by spring 29 which is secured to arm 28 and lever 17. A further object of lever 27 is to actuate plunger 30, slidable in a bore in frame 5 and urged into its retracted position by a spring 31; this plunger having as its purpose to feed or load a sealing cup 32 onto the lower extremity of pin 23. To seal the cup to the string or cord the curling die 22 is transferred into axial alignment with guide 33 slidable in a bore in frame 5 and urged into its upward position as shown by the spring 34, the excursion of guide 33 being limited by a stop screw 35 fitting into a slot in the guide. The upper portion of the guide has diametrically opposed V-shaped slots to facilitate the insertion of the ends of the cord or wire by the operator. Guide 33 has a central bore to accommodate an ejector pin 36 urged into its upward position by a spring 37 and held there by a stop screw 38. The upper portion of ejector pin 36 is hollow to receive a slidable shell shaped dividing pin 39 whose purpose is to facilitate division of the two ends

of the cord or wire when inserted into the guide by the operator, the dividing pin serves its purpose particularly where two ends of a cord or other fastening member are to be secured with the seal, the operator parting the cords sufficiently while inserting them so that the dividing pin is intermediate and guides one end in front of the ejector pin and the other behind it. This dividing pin is held in its upward position by a spring 40 which is extended to its free length. The downward movement of ejector pin 36 is caused by the downward stroke of the curling die 22 when lever 17 is actuated by cam 9, and is limited by a stop screw 41.

The application of a seal to the cord or wire requires a complete revolution of cam 9. In order to disengage the clutch when the revolution has been completed the operator releases lever 15 whereby spring 42 returns link 16 to the "off" position allowing stop lever 12 to revolve counterclockwise until resting against stop 43 extending from frame 5, whereby pawl 10 is thrown out of engagement after it has come in contact with stop lever 12. In order to provide an interlock to disengage the clutch after each sealing cycle regardless of whether the operator releases lever 15 or not, an arm 44 extends from link 16 through a hole 45 in frame 5 to be pushed downwardly by roller 26 when the latter descends due to cam 9, overcoming spring 46 which serves to urge link 16 into engagement with lever 12. The latter is pivoted at 47 on a pin extending from frame 5. 48 indicates the hopper in which the pre-fabricated sealing cups are placed. The type of cup chosen by way of example is shown in Fig. 2. It has two diametrically opposed slots which serve to accommodate the passage of the cord and are used in this embodiment of the hopper to keep the cups lined up until they are delivered to the die. The hopper has a drive shaft 49 revolving in the direction of arrow 50 and is driven by a belt 51 from the hub of clutch member 8 which has a groove to serve as a pulley.

The hopper mechanism is shown more clearly in Fig. 3. The principle used to feed the cups in order to the press is to provide a rotating disc which carries cups from the hopper by means of a magnet, and a restricted passage having the outline of a cup to permit passage of a cup to the track only when it is in the proper position. The disc to carry the cups from the supply at the bottom of the hopper to the track is indicated by 52. It is secured to a wheel 53 pinned to shaft 49 carrying a permanent magnet 54 to revolve therewith. It is necessary that disc 52 is of a non-magnetic material such as aluminum or brass.

The hopper mechanism is supported by the members of a track which serves to guide the cups from the hopper to the press mechanism. 55 designates one member of the track mechanism which has a bearing for shaft 49 and supports the guide rail 56 which engages the slots of the sealing cup. The track member 55 at its upper portion is secured to the hopper housing with the inter-position of a spacer 57 which, in conjunction with member 55 and wheel 53, serves to provide a restricted passage 58, shown in Fig. 5, which permits a cup to pass when it is in the proper position with the bottom of the cup against disc 52. If the cup is in a reversed position it is apparent that passage through opening 58 would be impossible. The lower extremity of member 55 of the track is bolted to frame 5 by means of bolt 59 with spacers 60, 61 and back 62 interposed. Secured with the same bolt is a stop 63

which serves to arrest curling die 22 in a vertical position when arm 28 is moved to the extreme right due to the action of cam 9. To permit removal of a cup loaded onto pin 23 when die 22 is swung into alignment with guide 33 the rail 56 is terminated at 64. Back 62 at its lower extremity is bored out in alignment with the bore in frame 5 to permit passage of plunger 30. Member 55 has a semi-circular clearance at 65 to accommodate cup 32 when it is pressed onto pin 23 by plunger 30.

Referring to Fig. 4 guide rail 56 is positioned the proper distance from wheel 53 to allow the cup 32 to slide downwardly when diametrically opposed slots are in line with the guide rail. Since it is preferable that wheel 53 is made of metal for greater durability, the coefficient of friction is rather small, and it is, therefore, necessary that the main weight of cup 32 rests on wheel 53 and that the friction between the cup and the guide rail is small. For this purpose I extend the guide rail such a distance that the cup when in contact with it is nearly at the top center of wheel 53 but is sufficiently past the top dead center so that it has a tendency to roll onto the guide rail 56. 50 indicates the direction of rotation of shaft 49 as well as disc 52 and wheel 53, whereas cup 32 is rotated in a clockwise direction as indicated by arrow 66. It will be observed that Fig. 4 is a section taken on line 4-4 of Figure 3 whereby member 55 is not shown. The shape of member 55 is intended to conform with the curve of the upper extremity of guide rail 56, as the latter is secured to member 55. Another portion of member 55 extends over to spacer 57 at which point member 57 and hopper housing 48 are secured together. Referring to Fig. 1, the hopper housing extends to the guide rail 56 and may be secured to member 55 in any convenient manner.

Having thus described the details of the novel invention, I shall now illustrate the operation of the same. The sealing press as shown in Fig. 1 is shown in the "off" position where the press members as well as cam 9 are at rest, but where shaft 6, clutch 8, as well as shaft 49, are revolving at a low speed of revolution. Pin 23 carries a cup 32. The diameter of pin 23 at its lower extremity is so proportioned that when a cup is pressed against it, it is held by friction. Assuming no what the operator wishes to apply a cup shaped member of the type shown in Fig. 2 to a cord or the like, the operator places the ends of the cord which may extend from an article or package that is to be sealed, into guide member 33. For this purpose it is necessary that he holds the article with one hand and with the other holds the ends of the cord slightly separated. By placing the cords over separator pin 39 and pulling them downwardly they become completely separated, whereby one end will slide to the bottom of the annular groove in guide member 33 behind ejector pin 36 and the other will be in front of ejector pin 36. The operator holds the cord firmly against the bottom of the V-shaped grooves in guide member 33. While doing so, he depresses bell crank 15 to rotate it in a counterclockwise rotation as viewed in Fig. 1, causing link 16 to move towards the rear of the sealing machine to operate lever 12 turning it in a counterclockwise rotation, whereby pawl 10 is urged into engagement with clutch 8 by action of spring 14. Since clutch 8 is revolving cam 9 is forced to revolve with the latter in unison because the pivot pin 11 or pawl 10 extends from or is a part of cam 9. A small degree of revolu-

tion of cam 9 allows lever 27 to turn in a counterclockwise rotation by virtue of spring 29 whereby arm 28 moves curling die 22 forward into alignment with guide member 33. Arm 28 is so proportioned that when it abuts against stop 63 curling die 22 is axially aligned with the guide member 33. As cam 9 revolves further, lever 11 rotates about stud 18 in a counterclockwise rotation depressing curling die 22 in the direction of guide member 33.

While curling die 22 descends towards and into guide member 33 the bottom of cup 32 on pin 23 comes in contact with divider pin 39 and presses it into ejector pin 36 until the top portion is flush with the top of pin 36, when the two parts are depressed in unison, causing spring 37 to compress. As die 22 is further pressed downwardly the cup enters the bore in which ejector pin 36 slides until the annular groove in guide member 33 comes in contact with the semi-curved rim of cup 32. The primary object of this guide member and of the annular groove is to bring the cord into immediate contact with the rim of cup 32. At a position where the rim of cup 32 comes in contact with the annular groove of guide member 33 ejector pin 36 abuts against stop screw 41 whereby movement of pin 23 is completely arrested and spring 24 is compressed as curling die 22 continues to descend. It is apparent that it is necessary that spring 24 is of greater stiffness than spring 37, spring 40 or spring 34 because the latter are to be overpowered by spring 24. While pin 23 as well as the bottom of cup 32 are held stationary and die 22 continues to descend the rim of cup 32 is curled over outwardly, i. e., as an outward curl. During this operation guide member 33 through its annular groove gently presses the ends of the cord against the curl of cup 32 so that the end of the rim of the latter is wrapped around the cord. The slots of cup 32 are lined up with the V-shaped slots of guide member 33 through which the cord passes. Cam 9 is so proportioned that at the point where the lift has reached its maximum, the curl is completely formed, whereby the cup is firmly secured to the cord and forms the finished seal.

As cam 9 continues to revolve in the same direction, lever 17 starts rotation in a clockwise direction urged by spring 29 which contracts, whereby curling die 22 moves upwardly and the completed seal is ejected due to the action of the various springs causing the members of the die and guide to return to their "off" position. Cam 9 comes in contact with roller 26 and forces lever 27 to revolve in a clockwise rotation whereby die 22 is urged into a vertical position in alignment with plunger 30 by virtue of spring 21. While in this position lever 27 is further rotated by cam 9 and presses plunger 30 upwardly to push cup 32 onto pin 23 on which it is held by friction. As the cam passes roller 26 lever 27 is allowed to again turn in the counterclockwise rotation so that arm 28 pushes die 22 into the position as viewed in Fig. 1. When cam 9 nears the position as indicated in Fig. 1, pawl 10 comes in contact with lever 12 and is consequently thrown out of engagement with clutch 8. Cam 9 is thus arrested, owing to stop 13 and lever 12. To provide a safety factor I incorporate the interlock 44 which is depressed by roller 26 when cam 9 moves the latter downwardly, whereby link 16 is thrown out of engagement with lever 12 even though the operator maintains the pressure on bell crank 15. Thus it is necessary for the operator to release

bell crank 15 before another sealing cycle can be started.

The operation of the hopper mechanism is continuous and not interrupted by the sealing mechanism. Assuming that a supply of cups is placed in hopper 48 and that shaft 49 is rotated in the direction of arrow 50, the magnetic force of magnet 54 attracts cups which are nearest to disc 52 and are carried upwardly toward the top of the hopper. The cups have a tendency to lie flat against disc 52 and thus are in a natural position to enter the track mechanism leading to the sealing means. The function of opening 58 which allows a cup in the desired position to pass is self-explanatory. If a cup is in the proper position and reaches the top dead center of wheel 53, the latter has a tendency to rotate it in the direction of arrow 66 after the magnet has passed it and the friction between the cup and disc 52 has ceased. As soon as the slots of cup 32 are lined up with the guide rail 56 the cup enters the track due to its own weight. In the several views the cups are omitted in the tracks in order not to encumber the drawings but in actual operation it is necessary that the track is filled to a reasonable height with a supply of cups because the lowermost cup is placed in alignment with pin 23 by virtue of the weight of the column of cups in the track. If the track is completely filled with cups and the topmost cup is therefore unable to enter even though the slots are lined up nothing serious can happen because an additional cup that is urged towards the top position immediately falls down again as soon as disc 52 and magnet 54 have rotated a short distance so that the cup is outside of the sphere of the magnetic force.

The lower portion of Fig. 3 illustrates the mechanism at the moment when a cup is pushed upwardly by plunger 30 onto pin 23, which is towards the end of a sealing cycle. In this position plunger 30 prevents the column of cups to move downwardly, but as soon as plunger 30 is retracted towards the "off" position as viewed in Fig. 1, the lowermost cup is pushed by the column of cups behind it onto plunger 30 to be axially aligned with it for which purpose the end of spacers 61 and 60 are formed to provide a stop for the cup.

It is apparent that the machine can be used in conjunction with fastening members other than cords or wires, but to simplify the description I am using the term "cord" to designate any type of fastening member such as a wire, or a string, ribbon, etc.

While I have shown only one embodiment by way of example I wish to make it understood that the invention can be carried out in ways different from that shown and applied to seals of various shapes without departing from the scope of the invention. Therefore, I do not wish to be limited in the construction nor in the application of the invention, except as defined by the terms of the claims.

I claim:

1. In a sealing machine for affixing cups having diametrically opposed slots to cords to form seals, where the ends of the cords are secured within the rims of said cups, in combination, a frame, a curling die supported by said frame, a revoluble shaft, a cam adapted to revolve with said shaft, lever means pivoted to said frame and actuated by said cam, a curling punch cooperating with said die and operatively connected with said lever means to be actuated thereby, a control lever pivoted to said frame and responsive to said cam

arranged to force said punch into alignment with said die, resilient means to urge said punch to retract from alignment with said die, a hopper adapted to contain a supply of cups of the type described, a track leading from said hopper to a fixed place near said die and not in axial alignment therewith, means to place cups in orderly fashion onto said track to be guided to said fixed place, a stop to arrest said punch in axial alignment, with the cup positioned in said fixed place when said punch yields to said resilient means, and means operated by said cam to attach a cup positioned in said fixed place onto said punch when aligned with said cup, said cam being arranged and mounted to produce an operating cycle where said control lever is actuated first to bring said punch into alignment with said die, second, said lever means is actuated to inject said punch into said die to curl the rim of a cup attached to said punch, third, said punch and said control lever are retracted so that said punch moves into alignment with said cup due to said resilient means and fourth, said means for attaching a cup to said punch is actuated.

2. In an automatic sealing machine for affixing cups having diametrically opposed slots to the ends of cords to form seals, said ends being secured within the rims of said cups in the finished seals, in combination, a frame, a drive shaft revoluble in said frame, a cam arranged to revolve with said shaft, a double armed lever fulcrumed to said frame, one arm thereof having a follower to follow the contour of said cam and the other arm having pivoted thereto a curling die comprising a punch member slidable within said curling die and being adapted to hold a cup of the type described, a spring to urge said punch member in a partly ejected position relative to said curling die, an ejector pin below said die and slidable with respect to said frame, a stop on said frame to arrest said ejector pin to cooperate with said curling die, a guide member coaxial with said ejector pin and slidable with respect to the

latter and said frame, spring means to urge said guide member towards said curling die, said guide member having an annular curling groove and a rim with diametrically opposed slots to receive

5 the ends of a cord, a control lever pivoted to said frame, one arm thereof contacting the contour of said cam, another arm being adapted to engage said curling die to swing the latter into axial alignment with said ejector pin and guide member, and a third arm of said control lever operating outside of the axis of said ejector pin, means for supporting a cup of the type described near said third arm, and resilient means to urge said curling die to swing into a position in axial alignment with said means for supporting a cup.

10 15 3. The construction as claimed in claim 2, and a dividing member at the free end of said ejector pin to facilitate the parting of the ends of a cord by the operator when inserting them in said guide member, said dividing member having a spring to yieldingly urge it to project out of the free end of said ejector pin, the latter being adapted to receive said dividing pin within itself.

20 4. The construction as claimed in claim 2, together with an operable clutch to engage said cam with said drive shaft to revolve therewith and means operable by the operator to disengage said clutch.

25 5. The construction as claimed in claim 2, together with a track for guiding sealing cups, said track being secured to said frame and leading to said means for supporting a cup.

30 35 6. The construction as claimed in claim 2, together with a hopper adapted to contain a supply of sealing cups, a track leading from said hopper to a point outside of said ejector pin and guide member to lead cups from said hopper to a place in alignment with said third arm of said control lever and a stop to arrest the lowermost cup when in alignment with said third arm so that a cup may be pushed onto said punch by said third arm.

40 WILLIAM STELZER.
